FIG. 5.

UNITED STATES PATENT OFFICE.

JOHN DAVID PEACE, OF PETERBOROUGH, ONTARIO, CANADA.

FIGURE TOY.

Application filed May 17, 1926. Serial No. 109,790.

My invention relates to improvements in toys, and the object of the invention is to devise a toy which when drawn along the floor by the child will give the effect of a 5 doll turning somersets continuously as it is drawn longitudinally, and it consists essentially of the arrangement and construction of parts as hereinafter more particularly explained.

10 Fig. 1 is a perspective view of my toy. Fig. 2 is a similar view to Figure 1 inverted.

Fig. 3 is an inverted plan.

Fig. 4 is a plan section.

15 Fig. 5 is a vertical section in the position assumed when the handle is not used.

In the drawing like characters of reference indicate corresponding parts in each figure.

20 1 indicates a spherical body in which may appear a suitable facial design such as indicated.

25 The body 1 is provided with parallel orifices 2 and 3, an orifice being located at each side of the centre and provided with opposing guideways 2^x and 3^x.

30 4 and 5 are slidable members, one end 4° of each member representing an arm in an extended position above the head as in Figure 1 on the inclined end faces 4^x of which may be represented an extended hand.

35 The opposite end of the members 4 and 5 is provided with a foot portion 6 which is turnably connected to each member end opposite to the arm end 4° preferably by forming an end orifice 5° in each member 6 and a stem 6^x on each member 4 and 5 frictionally fitting within the orifice 5°. By this means each foot may be adjusted horizontally to any angular position.

40 Each member 4 and 5 is provided intermediately of its length with a longitudinal slot 5^x. 7 is a cross pin extending through the slot walls and transversely of the slot and on which is freely mounted a disc roller 45 travelling in the guideways 2^x and 3^x.

49 9 is a bail member having inturned ends 9^x fitting into depressions or orifices 10 located in diametrically opposite positions in the body 1.

11 is a handle which may be of any suitable length secured to the bail member as indicated and which the child holds to draw the toy over the floor.

When the toy is drawn over the supporting surface by means of the handle 11, the feet are preferably set in a position at right angles to the line of travel or at such an angle as that shown with the spherical body always in contact with the supporting surface as clearly indicated in Figure 3.

As the child draws the toy in the direction of arrow Figure 1 the body 1 rolls over the flat surface until the end faces 4^x contact with the floor causing the members 4 and 5 to slide through the orifices 2 and 3 so that the feet portion 6 pass from the position indicated by dotted lines in Figure 2 to the full line position. The toy may be used without the handle 11 and in this case the feet members 6 are set parallel to the line of action. As 70 the roller action takes place the heels 12 which may be of rubber contact with the floor carrying the members 4 and 5 in a reverse direction back to their normal position indicated in Figure 1 thereby giving the effect of a somerset.

75 What I claim as my invention is:

1. A toy comprising a spherical body having parallel orifices extending therethrough one at each side of the body centre and having opposing guiding grooves extending longitudinally thereof, a member slidably held in each orifice to protrude from the ends thereof, rollers revolvably carried by the member and running in the guiding grooves, and a handle pivoted to the body at diametrically opposite points and in a plane at right angles to the plane in which the members have movement.

2. A toy comprising a spherical body and parallel orifices extending therethrough, one at each side of the body centre and having opposing guiding grooves extending longitudinally thereof, a member slidably held in each orifice to protrude from the end thereof, and a roller revolvably carried by each member and running in the guiding grooves.

JOHN DAVID PEACE.
